UNITED STATES PATENT OFFICE

160,995

COMBINED FLEXIBLY CONNECTED FRONT
AND REAR VIEW MIRRORS AND MOUNT-
ING SUPPORT THEREFOR

Mary F. Busa, Lakewood, Ohio

Application June 17, 1948, Serial No. 147,026

Term of patent 14 years

(CL. D86—10)

To all whom it may concern:

Be it known that I, Mary F. Busa, a citizen of the United States, residing at Lakewood, county of Cuyahoga, and State of Ohio, have invented a new, original, and ornamental Design for Combined Flexibly Connected Front and Rear View Mirrors and Mounting Support Therefor, of which the following is a specification, reference being had to the accompanying drawing, forming a part thereof.

Fig. 1 is a perspective view of a combined flexibly connected front and rear view mirrors and mounting support therefor, showing my new design;

Fig. 2 is a side elevation of the two mirrors with the lower part of the support broken away;

Fig. 3 is an enlarged view of the front of the front view mirror, and showing the rear view mirror in perspective and at one side, and also showing the vertical support broken away.

I claim:

The ornamental design for combined flexibly connected front and rear view mirrors and mounting support therefor, as shown.

MARY F. BUSA.
